FABRIC ROLL EDGE PROTECTOR

Joseph H. Bowman, Pittsburgh, Pa.

Application February 24, 1933. Serial No. 658,294

5 Claims. (Cl. 206—59)

This invention relates to fabric roll edge protectors.

Fabric roll edge protectors generally consist of metal caps held against the ends of hollow rolls of fabric material by tie members extending through the rolls. Such caps protect the edges of the fabrics from injury, and they also close the axial openings through the rolls so that materials such as nails and adhesive, which are to be used with the fabrics, may be stored and shipped in the compartments thus formed.

Heretofore, these tie-rods have had various disadvantages, such as being relatively expensive to manufacture, difficult or time-consuming of attachment, comprising loose parts, or requiring special tools for fastening them in place or for removing them. With these and other disadvantages the roll protectors known previously have added unduly to the cost of fabric rolls, and have otherwise been unsatisfactory and time wasting.

It is among the objects of this invention to provide a fabric roll edge protector which is simple in form, strong, inexpensive to manufacture, easy to apply and remove, and which can be quickly attached without the necessity of special tools.

The preferred embodiment of the invention is illustrated in the accompanying drawing, of which Fig. 1 is a side view of a protected fabric roll, shown partly in section; Fig. 2 an end view thereof; and Fig. 3 a side view of a cap-retaining member.

Referring to the drawing, a roll 1 of material, such as tar paper, building felt or other materials subject to damage at the ends, and having the customary axial opening 2 therethrough, is engaged at each end by a metal cap 3 which is intended for protecting the end of the roll (edge of the fabric) from injury. These caps also cooperate with the axial opening to form a closed compartment 2a suitable for housing related materials. Each cap is preferably formed with a centrally disposed depressed or dished portion 4 extending into the axial opening of the roll. One of the purposes of this dished portion is to prevent the cap from moving laterally, that is, radially of the roll. By having the dished portions snugly engage the interior of the openings the ends of the roll are reinforced.

The caps are held against the ends of the roll by a cap-retaining member, or tie-rod, 6. In accordance with this invention, this cap-retaining member is of elongate form, preferably wire. It is provided at one end with detent means

adapted to prevent that end from passing through the apertures in the caps, e. g. a loop 7 formed by doubling back the end portion of the wire and twisting it upon itself. This loop is large enough to prevent it from being drawn through 60 wire-receiving apertures 8 in the centers of the caps.

In order to permit the wire to be inserted through the cap apertures, and at the same time to enable it to be quickly and easily locked in 65 place by a simple operation not involving the use of special tools, the opposite end of the wire is provided with a loop 9, Fig. 3, formed in the same way as loop 7. Prior to use this loop is narrow, that is, flattened, longitudinally of the 70 wire so that it can be passed through apertures 8.

In assembling the roll edge protector, narrow loop 9 is passed through aperture 8 in one of the caps, and the cap is permitted to slide along the wire until at the opposite end of the wire it 75 meets the wider loop 7 which engages its outer face. This cap is then placed flush against the end of the roll with its dished portion 4 extending into the axial opening in the roll and with the wire extending through the roll. The flattened 80 loop, which projects from the opposite end of the roll, is passed through the aperture in the other cap. This cap is then slipped along the loop until it too lies against the end of the roll with its dished portion extending into the roll opening. 85 The flattened loop is then expanded or spread transversely in order to bring the widened loop 9a into engagement with the outer face of the adjacent cap to prevent it from being withdrawn through the cap aperture. 90

In this manner the caps are locked on, or tied together by, the wire, with the loops lying within the dished portions 4. Of course, it is apparent that the end loops are spaced no farther apart than the caps, so that the latter are not given 95 any play relative to the roll. In fact, it is preferable that the distance between the loops, before expansion of the narrow loop, be a little less than that between the caps. Then, when the narrow loop is expanded the wire is pulled taut, drawing 100 the caps tightly against the roll ends. See Fig. 1. Any suitable means may be used for spreading the narrow loop, no tool made especially for this purpose being necessary.

In a roll edge protector constructed in accordance with this invention, the tie rod may be made from comparatively thin wire because, in spite of its thinness, it requires considerable outward pressure of the caps against the loops to flatten them out. Consequently, materials intended for 105 110

use with the fabric of the roll may be safely stored and shipped in the axial opening 2. The cost of manufacturing this cap-retaining member is small because of its simple form, and because 5 of the light wire from which it is made. Furthermore, no difficulty is encountered in assembling the protector, and the narrow loop may be spread quickly and easily by tools usually found at hand.

10 According to the provisions of the patent statutes, I have explained the principle and mode of operation of my invention, and have illustrated and described what I now consider to represent its best embodiment. However, I desire to have 15 it understood that, within the scope of the appended claims, the invention may be practiced otherwise than as specifically illustrated and described.

I claim:

20 1. Cap-retaining means for use with a roll of material having an axial opening therethrough closed at each end by a removable apertured cap adapted to protect the ends of said material, said means comprising an elongate member provided at one end with a longitudinally flattened twisted loop adapted to be passed through the apertures in both caps, and provided at the opposite end with detent means incapable of passing through said apertures, said flattened 25 loop being adapted to be expanded into contact with the outer face of one of the caps to thereby lock said caps on said member and against the ends of the roll.

25 2. Cap-retaining means for use with a roll of material having an axial opening therethrough and a removable apertured protective cap at each end, said means comprising a wire provided at one end with a longitudinally flattened twisted loop adapted to be passed through the apertures in both caps, and provided at the opposite end with a wide loop incapable of passing through said apertures, said flattened loop being adapted to be expanded into contact with the outer face of one of the caps to thereby lock said caps on 40 said wire and against the ends of the roll between said loops.

30 3. The combination with a roll of material having an axial opening therethrough, of a roll edge protector comprising a protective cap dis-

posed against each end of the roll and provided with an aperture opening into said axial roll opening, and a cap-retaining member extending through said cap apertures and provided at one end with detent means engaging the outer face 80 of one of the caps, and provided at the opposite end with a longitudinally flattened twisted loop capable of being passed through said cap apertures and adapted to be expanded into contact with the outer face of the adjacent cap to 85 thereby tie said caps together against the ends of the roll.

4. The combination with a roll of material having an axial opening therethrough, of a roll edge protector comprising a protective cap disposed against each end of the roll and having centrally thereof a dished portion fitting within said axial opening for preventing lateral movement of the cap, the dished portion being provided with a wire-receiving aperture, and a tie-wire extending through said cap apertures and provided at one end with a loop engaging the outer face of one of the caps, and provided at the opposite end with a longitudinally flattened twisted loop capable of being passed through 100 said cap apertures and adapted to be spread transversely of the wire into contact with the outer face of the adjacent cap to thereby lock the caps on the wire and against the ends of the roll.

5. The combination with a roll of material having an axial opening therethrough, of a roll edge protector comprising a protective cap disposed against each end of the roll and having centrally thereof a dished portion fitting within 110 said axial opening for preventing lateral movement of the cap, the dished portion being provided with a wire-receiving aperture, and a one-piece tie-wire extending through said cap apertures and provided at one end with a loop engaging the outer face of one of the caps, and provided at the opposite end with a longitudinally flattened twisted loop having its inner end lying within the aperture of the adjoining cap and projecting outwardly therethrough, whereby when said outwardly projecting portion is expanded the wire is pulled taut between the caps to draw them tightly against the ends of the roll.
